(57) **CLAIM**

The ornamental design for a rolled biomass product for smoking, as shown and described.

DESCRIPTION

FIG. 1 is a side, left perspective view of a first embodiment of a rolled biomass product for smoking showing my new design;

FIG. 2 is a side elevation view of the design shown in FIG. 1, with all other sides being identical thereto and therefore not illustrated in the drawing disclosure;

FIG. 3 is a left end view of the design shown in FIG. 1; FIG. 4 is a right end view of the design shown in FIG. 1; FIG. 5 is a side, left perspective view of a second embodiment of a rolled biomass product for smoking;

FIG. 6 is a side elevation view of the design shown in FIG. 5, with all other sides being identical thereto and therefore not illustrated in the drawing disclosure;

FIG. 7 is a left end view of the design shown in FIG. 5; and, FIG. 8 is a right end view of the design shown in FIG. 5. The broken lines shown in the figures are included for the purpose of illustrating portions of the rolled biomass product for smoking that form no part of the claimed design.
